UNITED STATES PATENT OFFICE

HARRY R. PRIEST, OF LOUDONVILLE, OHIO

SHAVING BRUSH KIT

Application filed August 17, 1931. Serial No. 557,619.

This invention relates to shaving brush kits and has for an object to provide a shaving brush including a hollow grip or handle which may be used as a magazine for liquid soap or cream if desired or for storing shaving tools and accessories, the handle also being provided in the end with a mirror which may be used in an emergency as a shaving mirror.

10 A further object is to provide a shaving brush in which the bristle tuft is secured to the hollow handle by means of a single ferrule preferably formed of aluminum, although other material may be used, and including a bore which extends from end to end to receive the bristle tuft, which latter is provided with a hard rubber or other material base for anchoring the bristles of the tuft, which base is received in the bore of the 15 ferrule, the bore of the ferrule also being provided with a reduced exteriorly threaded neck for screwing the ferrule into the handle and being provided at diametrically opposite points in the threaded neck with set screws 20 which are screwed into the base, whereupon the ferrule and base may be cured as a unit and, when vulcanized, a rigid permanent assembly of the bristle tuft with the ferrule will be effected.

25 30 A still further object is to provide a shaving brush kit which is formed of a minimum number of simple inexpensive parts and which will be neat and attractive in appearance and in which the grip or handle may be stood on end without tipping over, the handle also being curved outwardly above and below the medial portion thereof to comfortably fit the operator's hand when shaving.

35 40 With the above and other objects in view the invention consists in certain novel details of construction and combinations of parts hereinafter fully described and claimed, it being understood that various modifications may be resorted to within the scope of 45 the appended claims without departing from the spirit or sacrificing any of the advantages of the invention.

45 In the accompanying drawing forming part of this specification,

50 Figure 1 is a longitudinal sectional view

through the shaving kit constructed in accordance with the invention and showing the grip as constituting a magazine for liquid soap,

55 Fig. 2 is a view similar to Fig. 1, with the ferrule shown in elevation, and with the handle forming a magazine for shaving tools and accessories,

60 Fig. 3 is an enlarged longitudinal sectional view through the ferrule,

Fig. 4 is a side elevation of a modified form of ferrule, and

Fig. 5 is a longitudinal sectional view through another modified form of ferrule.

65 Referring now to the drawing in which like characters of reference designate similar parts in the various views, 10 designates a hollow grip or handle which is preferably cylindrical in outline, and the outer surface thereof is preferably rounded outwardly, as shown at 11 and 12, above and below the medial point of the handle to comfortably fit the operator's hand. The bore of the handle is imperforate so as to hold a quantity of liquid soap, as shown at 13, or cream, if desired, 70 without the same leaking. The bore is threaded at the open end of the handle, as shown at 14, while the opposite closed end 15 of the bore is substantially flat and is provided with a countersink 16 therein on the outer face to 75 receive a mirror 17 which may be secured in the countersink by a split ring 18 or otherwise. The mirror may be conveniently used as a shaving mirror and, if desired, may be of the enlarging type to minutely view the 80 face for inspection.

85 The bristle tuft 19 of the shaving brush is provided with a base 20 formed of hard rubber or other suitable material in which the bristles are firmly anchored, and, preferably, 90 in the manufacture of the shaving kit, I employ a ferrule 21, assembled with the base before the final curing or vulcanizing step, as will now be described.

95 The ferrule 21 is provided with a substantially cylindrical bore 22 which extends throughout the ferrule from end to end to receive the base 20 of the bristle tuft. The bore is constricted near one end to provide an inwardly projecting annular flange 23 which 100

hooks over the base 20, as best shown in Fig. 1. The ferrule is gently rounded on the outer face, as shown at 24, from a point contiguous with said flange to a point substantially beyond the medial cross diameter of the ferrule, as best shown in Fig. 3. This rounded outer surface presents no projections which might lacerate the face when shaving. Beyond the rounded portion of the ferrule, the ferrule is reduced to provide a cylindrical neck 25 which is exteriorly threaded, as shown at 26, to engage the screw threads 14 of the handle. At the juncture of the neck 25 with the rounded portion of the ferrule, an annular shoulder 27 exists which seats upon the edge of the open end of the hollow handle, as best shown in Figs. 1 and 2 and limits insertion of the ferrule into the handle.

A pair of set screws 28 are threaded into the neck 25 of the ferrule preferably at diametrically opposite points thereof so as to extend into the bore of the ferrule and, when the set screws are advanced, the tips thereof will be embedded in the uncured base 20 of the bristle tuft. To complete the rigid unitary assembly of the bristle tuft with the ferrule, it is simply necessary to cure or vulcanize the bristle tuft and ferrule as a unit, whereupon the set screws 28 will become firmly set in the base during the vulcanizing operation. Thus, it will be observed that, in addition to the retaining flange 23, the ferrule is provided with set screws, both of which set screws and retaining flange coact with the base 22, and are cured in contact with the base, to permanently attach the bristle tuft to the ferrule.

Should the user not desire to equip the base with the liquid soap 13, as shown in Fig. 1, the bore or magazine of the handle 11 may be used to house shaving tools, such as a safety razor 29 and handle 30 therefor, tweezers 31, a caustic stick 32, and a double suction cup 33, the latter being used, of course, to attach the grip to a window pane or any other suitable flat support so as to present the mirror in front of the shaver's face when the need arises. Of course, other shaver's tools and accessories may be housed in the magazine in addition to or in lieu of those enumerated.

It will be particularly pointed out that the bristle tuft in the present embodiment of the invention is secured to the handle by means of a single ferrule in lieu of the usual multitude of parts ordinarily used to secure a bristle tuft to its handle, and that, furthermore, the single ferrule is permanently bound to the bristle tuft by means of the rubber base vulcanized against the entire bore of the ferrule, against the retaining flange of the ferrule, and against both set screws of the ferrule.

As shown in Fig. 4, I may dispense with the screws and thread the neck 34 of the ferrule 35 all the way through the shoulder 36 in some instances, or may even thread the

neck throughout and use the screws, as above described, instead of leaving a smooth band of unthreaded material at the screws, as illustrated in the preferred embodiment shown in Fig. 2. The value of threading the neck throughout is that this construction increases anchorage of the ferrule to the handle.

As shown in Fig. 5, I may thread the bore of the ferrule 37 throughout, as shown at 38, instead of leaving the bore smooth, as illustrated in Fig. 3. Obviously, by threading the ferrule throughout, the plastic material of the set will flow into the threads and, when hardened, the interfitting threads of hard rubber of the set and of metal of the ferrule will produce an extremely positive anchorage of the set in the ferrule. In this modification, I may use the screws 39, or may dispense with them entirely, if desired.

Having thus described the invention, I claim:

1. A shaving kit comprising a hollow handle forming a magazine, a bristle tuft, a rubber base anchoring the bristles of the tuft, a single ferrule having a bore vulcanized to the base, the bore being provided at one end with a retaining flange projecting over the end edge of the base, the ferrule being provided with a reduced exteriorly threaded neck remote from the retaining flange adapted to be threaded into the open end of the handle, and a pair of set screws threaded through said neck at diametrically opposite points therein and engaged in said base, said set screws coacting with said flange in permanently assembling said base to said ferrule.

2. A shaving kit comprising a hollow handle forming a magazine for the storage of shaving tools and accessories, the bore of said handle being threaded at one end and being closed at the opposite end, a shaving mirror countersunk in the outer face of said closed end, the outer surface of said handle being gently rounded outwardly above and below a substantial medial point of the handle to comfortably fit the operator's hand, a bristle tuft, a single ferrule having an exteriorly rounded portion devoid of projections and having a cylindrical bore provided at one end with an inwardly extending annular flange, a vulcanized base anchoring the bristles of said tuft and received in said bore below said flange, said ferrule being provided with a reduced exteriorly threaded neck adapted to be screwed into the threaded bore of the handle, said ferrule being rounded exteriorly from a point contiguous with said flange to a point contiguous with said neck to provide an annular shoulder adapted to seat upon the edge of said handle and limit insertion of the ferrule into said handle, and a set screw threaded into said neck and embedded in said base to coact with said flange in rigidly securing said base to said ferrule in permanent integral assembly.

3. In a shaver's kit, a hollow handle forming a magazine, a bristle tuft provided with a hardened plastic base, and a single ferrule for removably securing the tuft to the handle having a rounded exterior and having an axial bore, said ferrule being provided beyond said rounded exterior with a reduced exteriorly threaded neck adapted to be screwed into said handle, said ferrule being provided at one end of the bore with an interiorly projecting annular flange adapted to engage over said base, and a pair of set screws disposed at diametrically opposite points in said neck and embedded in said base for coacting with said flange in permanently securing said tuft to said ferrule in rigid unitary assembly.

4. A shaving kit comprising a hollow handle forming a magazine for the storage of shaving material, the bore of the handle being open at one end and internally threaded at the open end, a single ferrule having a bore extending from end to end thereof, said ferrule being reduced exteriorly to provide a neck, said neck being threaded to screw into the screw-threaded bore of the handle, there being a shoulder formed at the inner end of the threaded portion of the neck to engage the edge of the handle and limit insertion of the ferrule into the handle, and a bristle tuft rubber set in the bore of said ferrule.

5. A shaving kit comprising a hollow handle forming a magazine for the storage of shaving material, the bore of the handle being open at one end and interiorly threaded at the open end, a single ferrule having a bore extending from end to end thereof, said bore being threaded, said ferrule being reduced exteriorly to provide a neck, said neck being threaded to screw into the screw-threaded bore of the handle, there being a shoulder formed at the inner end of the threaded portion of the neck to engage the edge of the handle and limit insertion of the ferrule into the handle, and a bristle tuft rubber set in the bore of said ferrule, the rubber set entering the threads of the bore and when hardened forming a permanent assembly of the ferrule with the rubber set of the bristles.

In testimony whereof I affix my signature.
50 HARRY R. PRIEST. [L. s.]
